DUPLEX CENTRIFUGAL SEPARATOR

Sven C. Lindberg, New York, N. Y., assignor, by
mesne assignments, to Centrifugal Engineering
and Patents Corporation, New York, N. Y., a
corporation of New Jersey

Application March 7, 1930, Serial No. 433,888

8 Claims. (Cl. 233—45)

This invention relates to improvements in centrifugal separators by means of which a fluid can be separated from impurities of different specific gravities. While applicable to centrifugal separators in general, the invention relates more specifically to separators for removing foreign matter from aqueous suspensions of cellulosic material such as wood pulp, ground wood, cotton linters, bagasse, cornstalks, bamboo or other fibers.

10 Centrifugal separators of this type ordinarily consist of a cylindrical drum rotatable about its axis. The stock is fed in at one end and flows along the drum to the other end over one or more annular rings which extend inwardly from the drum. The stock flowing through the drum is held against the wall of the drum by the centrifugal force of rotation. The capacity of a separator of a given diameter, that is, the rate at which pulp can be passed through the drum and 15 properly purified, is limited. When the separator is first started up, the first pulp entering the drum forms a soft mat or lining within the drum over which flows the pulp stream. This mat combs the fibers in the stream and catches and 20 holds the dirt particles which are found therein. The heavier dirt particles gradually work through the drum toward the drum wall, while the mat itself tends to become gradually more compact. If an increase of capacity is attempted by 25 increasing the speed of rotation above the optimum speed, the mat tends to pack rapidly and thus to diminish its capacity for catching and holding dirt particles from the pulp stream. Thus the capacity cannot be increased beyond 30 a certain point by an increase of speed of rotation. The capacity of a separator of given diameter may, however, be nearly doubled by mounting a second drum within the first, sufficient 35 clearance being provided between the walls of the two drums for a stream of pulp to flow along the wall of the outer drum. A second stream is introduced into the inner drum and flows along the drum to the discharge end, where the streams from both drums may be discharged into a common receiving channel, or into separate receivers. This increase of capacity requires no additional floor space, so that a separator embodying the invention is especially advantageous where 40 available floor space is limited. As the diameters of the two drums preferably not not greatly differ, a speed of rotation which is just sufficient for the effective operation of the inner drum is suitable for satisfactory operation of the outer drum also. More than two concentric drums or shells

may be provided, but there is a practical limit to such multiplication of drums, owing to the fact that the drums must be spaced from one another, and if the difference between the diameter of the innermost drum and that of the outermost drum is too great, the difference between the centrifugal forces acting in these drums may be too great for satisfactory operation.

According to the present invention a separator mechanism is provided in which multiple concentric drums are combined with mechanism for supplying or feeding pulp stock thereto, the feeding mechanism being adapted to increase the efficiency of the several drums by decreasing the turbulence therein due to entering stock, and to afford a compact and convenient structure for the apparatus as a whole.

For a more complete understanding of the invention, reference may be had to the following description thereof and to the illustration thereof on the drawing, of which,—

Figure 1 is a side elevation of a centrifugal separator embodying the invention, a portion being broken away to show the interior parts in section.

Figure 2 is a plan view of the separator illustrated in Figure 1, but on a smaller scale.

Figure 3 is a fragmentary section on a vertical plane of the separator illustrated in Figure 1, on a larger scale. This figure also indicates the course of the pulp streams through the rotatable portion of the mechanism.

The separator mechanism comprises a plurality of coaxial drums mounted for rotation about their common axis. In the embodiment of the invention illustrated on the drawing, two drums 10 and 11 are shown, the outer drum being 10, the inner drum being 11. These drums are in general of a cylindrical shape, the lower end of the drum 10 projecting a short distance below the lower end of the drum 11. The drums are mounted as by a conical supporting member 13, on a vertical rotatable shaft 14 which may be driven by a suitable motor 15. The conical member 13 has an outwardly extending flange 16 at the lower end thereof on the rim of which is mounted the drum 10. This flange also carries the drum 11, the latter being supported by a series of connecting lugs 17. The drums may also be connected to each other and to the shaft at their upper ends by radial tie-members as at 9. Pulp is supplied to each of the drums at the lower end thereof, the pulp being pressed outwardly against the wall of each drum by the centrifugal force of the rotation of the drums. As additional pulp is supplied

to the lower ends of the drums, the pulp flows upwardly toward the top rim of the drums. The drums are each provided with one or more inwardly extending ribs 18 over which the stream of pulp must flow in its upward course. The upper portion 19 of each drum may be of somewhat greater diameter than the remainder of the drum, as shown on the drawing. At the upper end of this enlarged portion 19 is an inwardly extending flange 20 on the drum 10, and a similar flange 21 on the drum 11. These flanges are arranged to form an annular pool of stock in each of the enlarged portions 19, into each one of which pools dips a skimming ring. The ring 22 which dips into the pool formed in the upper end of the drum 10 may conveniently be secured to the outer surface of the drum 11. The inner skimming ring 23 which dips into the pool formed in the upper portion of the drum 11 may be supported by radially extending arms 24. The streams of pulp in the pools must flow under the respective skimming rings so that all impurities of lesser specific gravity than the pulp are caught by the skimming rings and retained until the apparatus is stopped and washed out. The depth of the pool can be regulated within limits by adjusting the skimming rings so as to vary the narrow passage or clearance between the skimming ring and the sharp edge of the adjacent flange 20 or 21.

It is desirable to supply to each of the drums a separate stream of pulp stock. To this end, according to the invention, a pair of conical members 25, 26 may be provided, these members extending downwardly, if desired, from short cylindrical members 27 and 28, respectively. The conical member 26 preferably extends down below the lower edge of the conical member 25, the lower edges of these members being arranged to be slightly above the lower ends of the respective drums. Thus stock supplied to the interior of the conical member 26 runs down the inner surface thereof and is discharged by centrifugal action from the lower rim to the inner surface of the drum 10. In like manner stock supplied to the inner surface of the conical member 25 runs down and is discharged to the inner surface of the drum 11. The members 25 and 26 are secured to the drums 10 and 11 and to the shaft 14 so that the drums and members rotate as a unit. Thus the stock which is fed into the upper ends of the members quickly acquires rotational motion around the common axis so that there is less disturbance of the pulp stream in the drums 10 and 11 than where the incoming stream has not had previous rotational movement impressed thereon.

In order to supply suitable pulp stock to the rotating conical members, I may mount above the upper ends of the conical members, or rather the cylindrical elements 27 and 28 from which the conical members depend, a supply trough which is divided by guiding members into a pair of branch channels 30 and 31. As shown in Figure 2, the delivery ends of these channels are bent around the axes of the drums in the direction of rotation. As each of the channels comes within its respective cylinder 27 or 28, the side of the channel 30 drops downwardly so as to extend below the lip of the cylinder 27, forming a guiding skirt as shown at 32 in Figure 3. In like manner the inner side of the channel 31 drops down to extend into the upper end of the cylinder 28, forming a guiding skirt as shown at 33. Pulp stock of suitable consistency is supplied through the channels 30 and 31, the curved delivery por-

tion of the channel serving to initiate the rotational movement of the stock, even before it comes in contact with the conical members 25 and 26. The rotation of these conical members greatly increases the rotative movement of the stock itself around the axis of rotation so that when the pulp stream reaches the lower ends of the conical members it is flung outwardly to the drums 10 and 11, but as it has acquired an annular speed of the drums there is little, if any, 10 tangential flow within the drums, so that the disturbance of the pulp mass within the drums by the incoming stock is the minimum.

The provision of such stock feeding means for the drums offers several advantages. Since the 15 conical members can be mounted within the inner drum, there is a considerable economy of space as the entire machine is not increased in external size by the addition of conical members within. Furthermore, a comparatively light construction is made possible since the upper ends of the drums can be secured by radially extending arms to the cylinder members 27, 28 which, in turn, may be secured to the supporting member 13 by spaced, radially extending links 9. The 20 stream of pulp flowing over the sharp edges of the flanges 20 and 21 are given a combing action by these edges which tends to break up fiber bunches and to smooth out the consistency of the pulp suspension. The streams issuing from 25 the two drums may be caught in a common receptacle or channel 35 extending around the periphery of the casing 36 which contains the drums. As shown on the drawing the drums 10 and 11 and the casing 36 may be provided with 30 suitable apertures in the bottom thereof to facilitate washing out the separator after use. The washing may be accomplished by simply playing a hose on the interior of the drums, the pulp mat being thereby washed down through the openings 35 in the bottom of the drums in the casing.

I claim:

1. Centrifugal apparatus for purifying paper pulp, comprising a plurality of coaxial drums radially spaced and rotatable about their common 45 axis, and means for supplying to each drum a stream of liquid to be purified, said supplying means including a plurality of conical members mounted coaxially within said drums and rotatable therewith, said conical members being 50 mounted with their larger ends radially inward of and adjacent to end portions of respective drums, means for feeding a stream of said liquid into each conical member at its smaller end, and means adjacent to the other ends of said drums 55 for collecting liquid discharged therefrom.

2. Centrifugal apparatus for purifying paper pulp, comprising a plurality of coaxial drums rotatable about their common axis, means for supplying to each drum a stream of liquid to be purified, said supplying means including a plurality of conical members coaxial with said drums and a plurality of troughs having delivery portions circling about the common axis of said conical members, each said delivery portion having a 65 lip extending downwardly into the upper end of a conical member, the lower ends of said conical members being in proximity to the lower ends of respective drums, and means adjacent to the upper ends of said drums for collecting liquid discharged therefrom.

3. Centrifugal apparatus for purifying paper pulp comprising a plurality of coaxial radially spaced drums rotatable about their common axis, the lower end of the outer drum extending be- 75

low the lower end of the inner drum, means for 5
rotating said drums, means for feeding stock to both said drums, said feeding means including a pair of conical members mounted within said drums for rotation therewith, the inner of said conical members having a lower edge on a level between that of the lower ends of the drums, the outer of said conical members having a lower edge a short distance above the level of the lower 10
end of the inner drum, means for directing separate streams of stock into said conical members, and means for collecting the purified streams of stock issuing from the drums.

4. Centrifugal apparatus for purifying paper 15
pulp, comprising a plurality of drums mounted one within another for rotation together about a common vertical axis, a collecting trough surrounding the upper edges of said drums to receive liquid discharged therefrom, and means for supplying separate streams of liquid to said drums 20
at their lower end, said supply means including a plurality of conical members mounted within the innermost drum for rotation therewith, the smaller ends of said conical members being uppermost, the larger ends of said conical members being in proximity to the lower ends of respective drums.

5. Centrifugal apparatus for purifying paper 25
pulp, comprising a plurality of coaxial spaced drums, one within another rotatable on their common axis, means at one end of said drums for collecting purified liquid discharged therefrom, and means for supplying each drum with a stream of liquid to be purified, said supply means 30
including a plurality of coaxial nested conical members supported within said drums for rotation therewith, the smaller ends of said conical members being adjacent to the discharge end of the drums, the larger ends of the conical members being adjacent to the other end of said drums, each conical member being supported and arranged to supply from its lower edge a stream of liquid to a corresponding drum, and means for guiding previously separate streams of liquid 35
into the small ends of the several conical members.

6. Centrifugal apparatus for purifying paper 40
pulp, comprising a plurality of drums one within another and rotatable on a common vertical axis, and means for feeding separate streams of liquid to be purified into the lower ends of the several 45
drums, said means including a plurality of conical

drums, said means including a plurality of conical hollow members coaxially rotatable with said drums, the larger ends of said members being lowermost and respectively opposite the lower end portions of corresponding drums, a plurality of non-rotatable guiding members above said hollow members, each said guiding member having a guiding skirt projecting into the upper end of a corresponding hollow member, and means for supplying separate streams of liquid to the 10
several guiding members.

7. Centrifugal apparatus for purifying paper 15
pulp, comprising a vertical rotatable shaft, a conical support member mounted on said shaft and rotatable therewith, said member having an outwardly projecting portion at its lower end, coaxial hollow drums supported by and rotatable with said support member, the lower ends of said feed members being respectively opposite the lower end portions of corresponding drums, and means for directing previously separate streams 20
into the upper ends of the feed members.

8. Centrifugal apparatus for purifying paper 25
pulp, comprising a vertical rotatable shaft, a support member secured to said shaft, said member extending outwardly and downwardly from the point of attachment to the shaft, said member also having a portion at its lower end projecting outwardly and provided with apertures of substantial area, an outer drum mounted on and rising upwardly from the rim of said outwardly projecting portion, an inner drum open at both ends supported by said outwardly projecting portion within the outer drum, and means for feeding separate streams of liquid to be purified 30
into the several drums, said feeding means including coaxial hollow members mounted on and rotatable with said support member, said hollow members having their lower ends respectively opposite to the lower end portions of the several 35
drums, means for directing previously separate streams of liquid into the upper ends of said hollow members, and means for collecting and uniting the separate streams discharged from the upper ends of the drums.

SVEN C. LINDBERG.
